CLUETT, PEABODY & COMPANY, INC., OF TROY, NEW YORK, A CORPORATION OF
NEW YORK.

COLLAR.

1,287,324.

Specification of Letters Patent. Patented Dec. 10, 1918.

Application filed August 31, 1916. Serial No. 117,953.

To all whom it may concern:

Be it known that we, HUBBARD F. HURD and SHELDON T. WRIGHT, citizens of the United States, and residents of Troy, in the county of Rensselaer and State of New York, have invented new and useful Improvements in Collars, of which the following is a specification.

This invention relates to turn-over collars, and particularly to collars of the type known as soft collars intended to be worn unstiffened, and characterized by an interior neckband and an exterior out-turned fold or top. Such collars have heretofore been formed 15 with a sewed button upon the outer side of the neckband, to take into a button-hole on the turned-over top, so as to fasten the top in place over the necktie. Such prior structures have the defect of being difficult to 20 iron smoothly, the presence of the button making it practically impossible to smoothly finish either the neckband or the exterior fold. A further objection to this type of collar lies in the frequency of breakage of 25 the sewed buttons in laundering. When a button is broken the collar is practically useless until another has been sewed on it.

This invention obviates the above defects in the collars of the prior art by providing 30 for the use of a button or buttons wholly detached from the fabric structure of the collar itself, and adapted by the structure hereinafter described to replace in effect the sewed button and to present an improved 35 appearance of the collar when it is in use.

In the accompanying drawings,—

Figure 1 is an assembled perspective view of the collar;

Fig. 2 is an enlarged section on the line 40 2—2 of Fig. 1;

Fig. 3 is an enlarged perspective view of one of the detachable buttons;

Fig. 4 is an enlarged section on the line 45 of 4—4 of Fig. 1 illustrating one form of button;

Fig. 5 is a view similar to Fig. 1 illustrating the use of a pair of connected buttons;

Fig. 6 is a plan of a detail of the assembled collar shown in Fig. 5; and Fig. 7 is an ele- 50 vation of a connected pair of buttons.

The collar comprises a neckband 1, which may be constructed as usual of multi-ply fabric. This neckband preferably includes internal stiffening members or reinforce- 55 ments 2, which aid in keeping the band up-

right, the collar being unstarched. These stiffening members may be distributed at the back of the collar as desired, for instance as shown, on either side of the central buttonhole 4, and at the front of the collar near each end. One end of the band 1 may terminate in the usual locking tab 5, and both ends thereof may be provided as usual with buttonhole 6, for attachment to the neckband and collar-button of the shirt with 60 which the collar is worn.

The top or outer flap 7 of the collar, of any desired outline, may be formed as a two-ply or multi-ply section sewed together in the usual manner, and attached to the neckband 1 in any desired manner.

The top 7 is provided with preferably elongate button-holes 8, which are preferably inclined at a substantial angle to the upper folded edge 9 of the top 7.

In the band 1, and inclined at an opposite angle or transversely to the button-holes 8, similar buttonholes 10 are provided in or near the neighborhood of, or passing through the substance of the stiffening reinforcements 2. The buttonholes 10 may be of the same dimensions as buttonholes 8, and when the parts are assembled the buttonholes 8 and 10 cross each other substantially at their middle parts, which relation is aided by the upper edge of the stiffener 2 acting to determine the place and direction of the fold and therefore the position of that part of the top 7 containing the buttonhole 8, in relation to that part of the band 10 containing the buttonhole 10.

While any desired form of button having a relatively small shank connecting a base and a head either flexibly or rigidly may be employed, a preferred form of button is that 95 illustrated in Figs. 3 and 4, comprising a metallic, celluloid or other colloid back 12, a base 13 preferably of metal, a shank 14 preferably formed as a closed loop, and an ornamental head 15 of mother-of-pearl or 100 other desired substance, simulating, if desired, a sewed button, the loop 14 taking under a bail 15 struck up from the back 13 and through holes 16 in the head 15.

The button head 15 in use is passed 105 through the buttonhole 10 from the rear and then through the buttonhole 8. When the button is in place the shank 14 is held by the oppositely disposed buttonholes at the middle of the buttonhole 8 in the top 110

7 and therefore so as to cause the top 15 to rest in the middle of the buttonhole 8 and conceal the greater portion thereof.

While the construction above described 5 may be employed in the manner indicated, a structure advantageous in use results from employing the device shown in Figs. 5, 6 and 7. Two button-heads 15 may be rigidly or otherwise attached by shanks 18 to a bar 10 or connector 19, so as to space the button-heads 15 at an appropriate distance apart to register with the buttonholes 8, 10, at both ends of the collar. The button-heads 15 are passed through the buttonholes 10 15 and 8, the crossing relation of which maintains the collar accurately in place, and assists the band 1 to lie smoothly in engagement with the neckband of the shirt to which the collar is attached.

20 What we claim is:

1. A turn-over collar of the soft collar type, comprising a neckband and a top, stiffening means in the band near each end adapted to determine the fold and conse-

quently the position of the top with respect 25 to adjacent parts of the band, said top and band respectively having buttonholes near each end adapted to be brought into registry when the top is in position for use, the band buttonholes being so located with respect 30 to the stiffening means as to derive support therefrom.

2. A turn-over collar of the soft collar type, comprising a neckband and a top, 35 stiffening means in the band near each end adapted to determine the fold and consequently the position of the top with respect to adjacent parts of the band, said top and band respectively having buttonholes near each end adapted to be brought into registry 40 when the top is in position for use, the band buttonholes being worked through the said stiffening means.

Signed by us at Troy, New York, this 25th day of August, 1916.

HUBBARD F. HURD.
SHELDON T. WRIGHT.
